Specification for Design.

Patented Apr. 13, 1920.

Application filed October 16, 1919. Serial No. 331,193. Term of patent 14 years.

To all whom it may concern:

Be it known that I, WILLIAM J. VAN OSDEL, a citizen of the United States, residing at Chicago, in the county of Cook and State of Illinois, have invented a new, original, and ornamental Design for a Handle for Hair-Clippers, of which the following is a specification, reference being had to the accompanying drawing, forming part thereof.

The figure is a plan view of a handle for hair clippers, showing my new design.

I claim—

The ornamental design for a handle for a hair clipper, as shown.

WILLIAM J. VAN OSDEL.
